UNITED STATES PATENT OFFICE.

ALBERT C. MURPHY, OF NEW YORK, N. Y., ASSIGNOR TO P. H. MURPHY COMPANY, OF PARNASSUS, PENNSYLVANIA, A CORPORATION OF PENNSYLVANIA.

METAL CAR-ROOF.

1,191,214.

Specification of Letters Patent. Patented July 18, 1916.

Application filed February 9, 1916. Serial No. 77,215.

To all whom it may concern:

Be it known that I, ALBERT C. MURPHY, a citizen of the United States, and a resident of the city of New York, in the county of New York and State of New York, have invented a new and useful Improvement in Metal Car-Roofs, of which the following is a specification.

This invention relates to flexible metal roofs for freight cars wherein the metal roof sheets extend from eaves to ridge and are loosely secured at the ridge and eaves to the roof substructure, and adjacent roof sheets are connected by non-rigid standing seams or joints.

The objects of the invention are to prevent tearing of the roof sheets in service, to do away with holes through the roof sheets for the securing means, and to provide for the convenient removal and replacement of worn and damaged roof sheets, and to maintain the joints between the roof sheets tight under service conditions.

The invention consists in the combination of a roof sheet having a curved ridge end with a ridge seam cover adapted to cooperate therewith to retain the roof sheet in place and to keep water out of the ridge joint.

Further objects of the invention appear in connection with the following description of the car roofs shown in the accompanying drawings; and what the invention consists in is more particularly defined in the appended claims.

In the drawings, wherein the same reference characters designate the same or similar parts in the several views, Figure 1 is a plan view of a portion of a car roof embodying the invention, the running boards and seam covers being partly broken away to show the roof sheets; Fig. 2 is a cross-section of the same at the eaves, on the line 2-2 in Fig. 1, drawn to a larger scale; Fig. 3 is a cross-section on the line 3-3 in Fig. 1, drawn to the same scale as Fig. 2; Figs. 4 and 5 are enlarged cross-sections of the ridge construction, on the lines 4-4 and 5-5 in Fig. 1, respectively; Fig. 6 is a plan view of the ridge ends of a pair of roof sheets of modified form, showing a suitable

ridge seam cover therefor detached; Fig. 7 is a cross-section of the ridge construction shown in Fig. 6; Fig. 8 is a plan view of the ridge ends of another modified form of the invention, showing a suitable ridge seam cover therefor detached; and Fig. 9 is a cross-section of the ridge construction shown in Fig. 8.

In the drawings, the invention is shown applied to a car having a wooden roof substructure consisting of roof boards 11 supported at their ends on a side plate 12 and ridge piece 13, but the substructure may be constructed in any manner desired of either wood or metal. The roof sheets 14 are arranged side by side in two rows on opposite sides of the ridge, the roof sheets in each row being spaced apart sufficiently to permit wooden battens 15 to be laid between them. The roof sheets on opposite sides of the ridge are arranged in alignment crosswise of the car, and the battens on each side of the car are in alignment and meet at the ridge. The ridge ends of the roof sheets are slightly convex, and the middle points of the curved extremities of opposite roof sheets nearly touch each other at the ridge lines midway between the battens.

The sides and ridge end of each roof sheet are provided with upstanding flanges 16 with inturned extremities 17 which slope down the body portion of the sheet. The side flanges of adjacent roof sheets are covered by side seam covers 18 which are supported on the battens 15. These side seam covers have side walls 19 which are turned in at their bottoms and the inturned edges 20 of which are hooked under the extremities 17 of the side flanges of adjacent roof sheets, as shown in Fig. 3. This construction provides a loose but watertight connection or joint between the sides of adjacent roof sheets. The invention is not restricted to this side seam construction, and any sufficiently flexible seam or joint for connecting the roof sheets along their sides may be used.

The eaves ends of the roof sheets are turned under, forming hooks or rebends 21 on their under sides which are hooked into the folded over inner edges 22 of flashing

- strips 23, as shown in Fig. 2. The flashing strips are nailed or otherwise secured along the eaves of the car between the battens. Angle-shaped eaves clips 24 are secured to 5 the side of the car below the ends of the roof sheets, with their top legs projecting inwardly over the eaves ends of the roof sheets 14 and side seam covers 18 to hold them down. The eaves clips are detachably secured to the fascia board 25 by bolts, and 10 may be quickly removed and replaced when desired. They rest loosely upon the roof sheets without clamping them, so the roof sheets are free to move both lengthwise and 15 crosswise of the car at the eaves. The invention is not restricted to this means of securing the roof sheets at the eaves, and any suitable method for loosely holding the eaves ends of the roof sheets may be used.
- 20 The ridge ends of the roof sheets are covered by ridge seam covers 26 which are inverted channel-shape, their side walls 27 having outwardly extending flanges 28 which rest on the roof sheets. Midway of their 25 length the side walls 27 of the ridge seam covers are provided with inwardly projecting semi-cylindrical bosses 29 extending from top to bottom. The two opposite bosses 29 of each ridge seam cover are adapted to 30 bear against the inturned extremities 17 of the ridge end flanges 16 of the underlying oppositely disposed roof sheets, and thereby the roof sheets are retained in position on the roof substructure against sliding down.
- 35 The roof sheets are free to pivot or swing on the bosses 29 and can thereby accommodate themselves to the distortions of the substructure which occur in service.
- The ridge ends of the side seam covers 40 18 and the ends of the ridge seam covers 26 are secured in position by square corner caps 30, the side walls 31 of which are recessed to fit over the seam covers. These corner caps are bolted to the ridge pole by bolts 32 which 45 also secure the running board saddles 33 in position. The running board saddles rest on the side seam covers 18 and battens 15. The running boards 34 may be secured to the 50 saddles in any suitable manner. The weight of the running board saddles and running boards is not carried on the roof sheets, which are freely movable under the side and ridge seam covers within the limits of the side walls thereof.
- 55 In the modified form of construction shown in Figs. 6 and 7, the ridge flanges 35 of the roof sheets 14 are straight instead of being curved, and the side walls of the ridge seam cover 36 have their lower edges turned in and 60 bent up to form trough-shape flanges 37. The inner walls of the troughs 37 are curved in so that the troughs are wider at the middle than at the ends. The middle points of the inside walls of the troughs 37 are adapted to

contact with the ridge flanges of the underlying oppositely disposed roof sheets and thereby form a pivotal support or fulcrum on which the roof sheets may bear.

In the modifications shown in Figs. 8 and 9, the ridge flanges 38 of the roof sheets are provided with inturned flanges which are inwardly curved from their ends to the middle line of the roof sheets. The side walls of the seam covers 39 have straight inturned flanges 40 adapted to bear against the middle 75 points of the flanges 38, and thereby to retain the roof sheets in place while permitting them to move around said points of contact to accommodate themselves to the distortions of the substructure in service.

80 It is evident that other modifications of the ridge construction can be made without departing from the invention, and this invention is not restricted to any one of the arrangements shown and described.

85 What I claim as my invention and desire to secure by Letters Patent is:

1. A flexible car roof comprising roof sheets having upstanding flanges at their ridge ends, the flanges of adjacent sheets approaching each other more closely at the middle than at the corners of the ridge ends of the sheets, ridge seam covers straddling the ridge flanges of oppositely arranged roof sheets, said seam covers having side walls 95 adapted to touch said ridge flanges at their middle points only, and means for retaining said ridge covers in central alinement on the car.

2. A flexible car roof comprising roof sheets oppositely arranged on each side of the ridge and having upstanding flanges at their ridge ends, the ridge flanges of opposite roof sheets curving toward each other at the middle of their length, said ridge flanges 105 having inturned top margins, ridge seam covers straddling the ridge flanges of oppositely arranged roof sheets, said seam covers having side walls provided with pivot bearings for said ridge flanges at their middle 110 points, and means for retaining said ridge covers on the car, said ridge covers having outturned flanges along the bases of their side walls which bear upon the roof sheets.

3. A flexible car roof comprising loosely 115 connected roof sheets having outwardly curved ridge ends, upstanding flanges along said ridge ends, ridge seam covers of inverted channel-shape covering said flanges, the side walls of said ridge seam covers having 120 cylindrical depressions at their middle points constituting bosses adapted to bear against the curved ridge flanges of said roof sheets.

4. A flexible car roof comprising a series 125 of pairs of oppositely disposed roof sheets extending from eaves to ridge and loosely connected along their side margins, the ridge

ends of said roof sheets being curved outwardly and provided with marginal flanges, the middle points of the roof sheets of each pair being located in proximity to each other, 5 ridge seam covers over the ridge flanges of said pairs of roof sheets, said ridge seam covers having inwardly projecting portions of midway of their sides which are adapted to

bear against said flanges near their middle points, whereby said roof sheets can pivot 10 on their mid-lines against each other and against said inwardly projecting portions of the ridge seam covers.

Signed at New York, New York, this fourth day of February, 1916.

ALBERT C. MURPHY.
